DESIGN FOR A GOGGLE

Samuel E. Bouchard, Rochester, N. Y., assignor
to Bausch & Lomb Optical Company, Rochester,
N. Y., a corporation of New York

Application January 14, 1939, Serial No. 82,346

Term of patent 14 years

To all whom it may concern:

Be it known that I, Samuel E. Bouchard, a citizen of the United States and a resident of Rochester, county of Monroe, and State of New York, have invented a new, original, and ornamental Design for a Goggle, of which the following is a specification, reference being had to the accompanying drawing, forming a part hereof.

Fig. 1 is a perspective view of a goggle embodying my new design.

Fig. 2 is a top plan view of the same with parts of the temple broken away for convenience of illustration.

I claim:

The ornamental design for a goggle, substantially as shown and described.

SAMUEL E. BOUCHARD.
